UNITED STATES PATENT OFFICE

HARRY E. GIBBS AND ORRIN J. VOGELGESANG, OF CANTON, OHIO, ASSIGNEES TO THE GIBBS MANUFACTURING COMPANY, OF CANTON, OHIO, A CORPORATION OF OHIO

DESIGN FOR A GAME BOARD

Application filed November 24, 1930. Serial No. 37,780. Term of patent 14 years.

To all whom it may concern:

Be it known that we, HARRY E. GIBBS and ORRIN J. VOGELGESANG, citizens of the United States, residing at Canton, in the county of Stark and State of Ohio, have invented a new, original, and ornamental Design for Game Boards, of which the following is a specification, reference being had to the accompanying drawing, forming part hereof.

We claim:

The ornamental design for a game board or similar article, as shown.

HARRY E. GIBBS.
ORRIN J. VOGELGESANG.
